ABSTRACT

An electromagnetic selector comprising a series of retractable stops which may be operated by an electromagnet energized by an electric current controlled by a magnetic contact through which the current is fed through an interrupter connected directly to a source of electric current.

ELECTROMAGNETIC SELECTOR

This invention relates to an electromagnetic device permitting to select, to arrange in order, and to control the successive operations of a mechanical, thermal, hydraulic, or electric machine, which machine may be manually or automatically controlled.

The electromagnetic selector, in accordance with the invention, is for automatically operating a control device or a number of electrical circuits in various positions in a predetermined sequence during predetermined time intervals and according to a predetermined cycle, while permitting to obtain as many different cycles and rapid transfer from one cycle to the other. In a first embodiment of the invention the selector comprises an electric motor having a driving shaft, an arm coupled to the shaft, a cylinder mounted adjacent the arm, a finger secured to the arm and adapted to move around the periphery of the cylinder, and a series of stops positioned around the periphery of the cylinder and adapted to be engaged by the finger during rotation thereof. The stop include contact bearing stops the contacts of which are connected to a timing relay, a timing stop for providing dead times in the operation of the control device or of the electrical circuits, and fixed stops located at both ends of the above-mentioned series of stops for energizing the motor. An interrupter is positioned adjacent the timing stop for stopping the motor.

In a second embodiment of the invention, the electric motor is coupled through an electromagnetic device to disengageable gears connected to a pinion which is secured to a worm gear adapted to engage the above-mentioned retractable stops which, in this embodiment, are positioned on a flat base.

The above-described electromagnetic selector finds application:

a. in the electrical and electronic fields to automatically regulate the energization of a predetermined number of circuits (control, lighting or power circuits) in a predetermined sequence, during predetermined time intervals, according to a predetermined cycle, while permitting to obtain as many different cycles as it is wanted with the same set-up and the rapid transfer from one cycle to the other on a same machine, such as, for example, regulation of traffic lights, control of various mechanisms of the control circuits of an automatic machine or of a machine which it is desired to render automatic;

b. in the mechanical field to automatically operate a control device (lever, wheel, etc.) in various positions, in a predetermined sequence, during predetermined time intervals, according to a predetermined cycle, while permitting to obtain as many different cycles as it is wanted with the same set-up and the rapid transfer from one cycle to the other;

c. in automatic sequential electromechanical or mechanoelectronic devices permitting to obtain the above-mentioned functions simultaneously.

The invention will now be disclosed with reference to preferred embodiments thereof and to the accompanying drawings in which:

FIG. 1 is a perspective schematic view of a work piece to be realized with the machine in accordance with the invention;

FIG. 2 is a schematic view of a selector in accordance with the invention using an arm, a cylinder and electromagnetically retractable stops;

FIG. 3 is a side view of the device illustrated in FIG. 2;

FIG. 4 illustrates a second embodiment of the system illustrated in FIG. 2;

FIG. 5 illustrates a third embodiment of the device in accordance with the invention; and

FIGS. 6 illustrates a schematic view of an electromagnetic retractable stop used with the selector device in accordance with the invention.

Let us take a drilling machine the operations of which are desired to be rendered automatic. The problem is as follows:

It is desired to drill six holes of various diameters D1 to D6 in a work piece 1 such as illustrated in FIG. 1. The holes are located on different circumferences and have between themselves various angles $\alpha'1$ to $\alpha'5$. Such a work piece is first positioned on a table which may be rotated by means of a control wheel 2 the angles of rotation $\alpha1$ to $\alpha5$ of which correspond to the above-mentioned angles between the holes of the work piece.

If the above work piece is manufactured manually, the work will be done as follows:

1. the work piece is placed on the table of the machine and fixed in position and the control wheel is rotated into starting position 1;

2. the chuck carrying slide bar used for drilling the first hole of diameter D1 is lowered and, after the hole is drilled, the slide bar is raised by its own return spring;

3. the control wheel of the drill is rotated an angle $\alpha1$ to bring it to position 2 and the table supporting the work piece 1 rotates an angle $\alpha'1$ and comes into position 2';

4. the chuck carrying slide bar is again lowered to drill the second hole of diameter D2 and, after drilling the hole, returns to its upper position under the control of its return spring;

5. the control wheel is rotated an angle $\alpha2$ to bring it into position 3 and the table rotates a corresponding angle $\alpha'2$ and comes into position 3';

6. the third hole of diameter D3 is drilled and so on until the sixth hole of diameter D6, and then the control wheel 2 is brought back to original position 1 by turning it in the opposite direction; the work piece is then removed from the table and replaced by a new one.

In the automatic operation of the drill, the lowering of the chuck is done by means of an electric motor the stopping of which frees the chuck to permit such chuck to return to its original position under the action of its own return spring. Let us call $t1, t2, \dots, t6$ the time intervals necessary for the drilling of the respective holes of diameters D1, D2, ..., D6. The apparatus, in accordance with the invention, will permit to obtain in a totally automatic fashion:

1. the angular positioning of the control wheel 2 (positions 1 to 6) during the desired time intervals ($t1$ to $t6$);

2. the feeding of current through the automatic devices during the desired time intervals permitting to lower the chucks for the drilling as soon as the control wheel 2 has reached the desired position;

3. the return of the control wheel 2 to the original position 1 when the sixth hole has been drilled and when the chuck has returned to its rest position;

4. the renewal of the cycle.

The apparatus illustrated schematically in FIGS. 2, 3 and 6 comprises an electric motor 3 having a driving shaft 5 upon which is keyed an arm 4 which is biased by a powerful spring 6 towards its extreme end of travel position. One of the ends of the spring 6 is connected to arm 4 while the other end thereof is connected to the stator of motor 3 or to a fixed piece. The arm 4 has at its free end a finger 7 which may be rotated around the periphery of a cylinder 8 upon which are mounted contact bearing retractable stops 9, the contacts of each stop being connected to a timing relay 10. A retractable timing stop 11 is provided to realize a dead time for installing and dismantling a work piece on the machine. Each contact bearing timing stop is connected to a timing relay for a time duration to The six contact bearing selection stops 9 are connected respectively to six timing relays 10 during time intervals t_1 to t_6 respectively. For the timing relays, the contacts permitting closure of the electromagnetic circuits of the six stops 9 are of the delayed type. The time delay thereof corresponds to the time necessary to permit the return of the chucks to their rest position once a hole has been drilled.

The extreme stop 16 is fixed, that is non-retractable. The energization of the motor 3 is insured by means of the timing relay of such fixed stop 12 at the time when the relay is "dropped". The stopping of the motor is insured by means of an interrupter placed under the timing stop 11.

The apparatus so far disclosed operates as follows:

The operator places a work piece on the machine and fixes it in position. He will then energize the motor 3 through a manual switch. The motor 3 will drive the arm 4 and the finger 7 connected thereto as well as the driving wheel 2 until the arm 4 gets into the original position. During movement of the arm 4, the selection stops 9 as well as the timing stop 11 are retracted by the arm 4 coming in contact with the can shape of the stops. When going past the timing stop 11, the switch associated with such timing stop stops the motor. The arm 4 being then biased only by its return spring 6 starts to move in the opposite direction. The finger 7 contacts the timing stop 11 and the contact of such timing stop feeds the winding of the timing relay of timing interval to The assembly of arm 4, finger 7 and control wheel 2 is thus immobilized. And the end of time interval t_0 (during which the operator has been able to place a work piece in position and eventually withdraw the one which has been previously machined) the relay of the timing stop 11 drops, the contact of the circuit of the electromagnet 17 operating the stop closes, the stop is retracted against the action of its return spring 18, the contact permitting the automatic feed of the winding of the timing relay is closed, the finger 7 is thus free and the arm 4 drives it against the following stop (ref. 1 of FIG. 3) under the action of spring 6.

The circuit for the automatic feed of the winding of the timing relay comprises a contact the opening of which is delayed by a few seconds. When such a contact opens, the winding of the timing relay is not energized any more and the timing relay comes back to its rest position. The contact of the circuit of the stop elec-

tromagnet is open, the stop is no more attracted and returns to its normal position under the action of its return spring (FIG. 6). The device is then ready for the next cycle.

The finger 7 is now in contact with stop 1 and the winding of the timing relay having timing interval t_1 is fed as well as the circuit No. 1 feeding the device controlling the lowering of the chuck for drilling the first hole of diameter D1. At the end of time interval t_1 , the timing relay drops and the winding of the relay is automatically fed by a contact which is closed and by another contact the opening of which is delayed. The contact of circuit No. 1 opens and stops the device controlling the lowering of the chuck. The chuck of diameter D1 returns to its rest position under the action of its return spring. The contact of the electromagnetic circuit of the stop which is delayed in its closure is then closed and feeds the electromagnet which attracts the stop against the action of its return spring. The stop frees the finger 7 which then comes in contact against stop No. 2, driven by arm 4, itself biased by its return spring 6. During this time, the contact, which contact has a delayed opening, of the automatic feed circuit of the timing relay relay is opened. The relay comes back to a rest position causing the contact of circuit No. 1 to open and electromagnet contact of the stop to also open. The stop is no more attracted and returns under the action of its spring causing the contact having a delayed opening of the automatic feed to close and the instantaneous automatic feed contact to open. The device is thus ready for the next cycle.

The operation is the same for stops 3 to 6.

When the timing relay (of timing period 26) of the stop No. 6 drops, the contact controlling the starting of the motor is closed. The motor drive the arm 4 and its finger 7 against the action of spring 6. The stops 9 are retracted because of their cam shape and, in retracting the last stop 11, such stop operated the interrupter controlling the stopping of the motor. The finger 7 is driven by the arm 4 in the opposite direction after the motor is stopped under the action of spring 6 and such finger 7 comes again in contact with timing stop 11 to start the cycle again.

In the second embodiment illustrated schematically in FIG. 4, there is used an arm 4 which may be disengaged in the case wherein rotation of the motor in both directions is required. The device may also be coupled with an electromagnetic clutch.

The embodiment using an arm with a return spring is possible when the total angle of rotation is relatively small and when it is necessary to return to a rest position in a direction opposite to the direction of selection.

In the third embodiment illustrated in FIG. 5 there is used an electromagnetic clutch 12 driving a disengageable gear 13 which is coupled with a pinion 14 secured to a worm screw driving a nut 15, which nut operates the contact bearing retractable stops 9. The operation of an additional contact opens the feeding circuit of the electromagnetic clutch and the arm or the nut is no more driven.

There may also be used a disengageable arm with an electromagnetic clutch together with a motor having two directions of rotation. The two directions of rotation of the motor are given by the relays of the extreme stops at a time when they drop.

There may be used one or plural disengageable arms, these operating in a completely independent fashion. The motor turns permanently in one direction or the other; this selection is done by the relays of the stops.

A disengageable arm 4 permits the driving thereof when such arm is not against a stop. It permits to obtain an adjustable contact force for the finger 7 against the contact bearing stop 9.

The driving of arm 4 may be done by means other than an electric motor.

The timing stop 11 may be located in any position with respect to the selection stops 9 each time that a dead time is needed.

In the case of selections having degrees of rotation higher than one full turn, the set-up of FIG. 5 must be used in one or two directions of selection.

The driving of the worm screw of FIG. 5 may be done not only by means of toothed pinions but also by pulleys and belts or by any other systems.

I claim:

1. Electromagnetic selector for automatically operating a control device or a number of electrical circuits in various positions, in a predetermined sequence, during predetermined time intervals, and according to a predetermined cycle, while permitting to obtain as many different cycles with the same set-up and the rapid transfer from one cycle to the other, comprising: a motor having a driving shaft; an arm coupled to said shaft; a cylinder mounted adjacent said arm; a finger secured to said arm and adapted to move around the periphery of said cylinder; a series of stops positioned around said cylinder and adapted to be engaged by said

finger, said stops including contact bearing retractable stops for operating said device or circuits, a retractable timing stop for providing dead times in the operation of said device or circuits, and fixed stops for energizing said motor; and an interruptor positioned under said retractable timing stop for stopping said motor.

2. Electromagnetic selector as defined in claim 1, wherein said arm is keyed to said shaft and is biased into an extreme end of travel position by a heavy spring one end of which is connected to the arm and the other arm of which is fixed to a stationary point.

3. Electromagnetic selector for automatically operating a control device or a number of electrical circuits in various positions, in a predetermined sequence, during predetermined time intervals, and according to a predetermined cycle, while permitting to obtain as many different cycles with the same set-up and the rapid transfer from one cycle to the other, comprising: a motor having a driving shaft; an electromagnetic clutch connected to said driving shaft; a gear coupled to said electromagnetic clutch; a pinion coupled to said gears; a worm screw driven by said pinion; a nut coupled with said worm screw; a series of stops located on a flat base adjacent said motor and adapted to be engaged by said nut, said stops including contact bearing retractable stops for operating said device or circuits, a retractable timing stop for providing dead time in the operation of said device or circuits, and fixed stops for energizing said motor; and an interruptor positioned under said timing stop for stopping said motors.
